UNITED STATES PATENT OFFICE.

FREDRICH J. RODE, OF CHICAGO, ILLINOIS, ASSIGNOR TO MARQUETTE TOOL & MANUFACTURING CO., OF CHICAGO, ILLINOIS, A CORPORATION OF ILLINOIS.

DIE CUSHION.

Application filed May 29, 1925. Serial No. 33,612.

Cushioning devices for sheet metal drawing presses generally comprise a cylinder supplied with fluid and in which cylinder resistance pressure is increased by means of 5 a piston reciprocable therein. The piston rod which extends beyond the cylinder is usually connected at one extremity to a pressure plate, commonly known as a pin plate for the reason that pins which support one 10 of the die members pass loosely through the bed plate of the machine and rest upon the plate. As pressure is exerted upon the die through the medium of the ram or some other reciprocable element in the machine the 15 plate and the pistons are correspondingly lowered through the medium of the pins and against the pressure in the cylinders.

In some instances when the pin plate is of a considerable area a number of cylinders 20 are used and the piston rods are each connected with the pressure or pin plate.

It has been found that under such conditions the pressure or pin plate is not always maintained in a horizontal position during 25 its lowering movement due, among other things, to the fact that a greater pressure will be exerted at some points throughout the area of the plate than at others, resulting on account of the rigid connection, in a 30 binding of the parts with the ultimate resulting injury.

It is one of the objects of the present invention to overcome these difficulties and objections and to provide an improved flexible 35 connection between the end of the piston rod and the pressure or pin plate which will yield when the plate is tilted or moves out of the horizontal position and at the same time will not interfere with the plate being 40 subjected to the full resistance pressure of the fluid in the cylinder.

To the attainment of these ends and the accomplishment of other new and useful objects as will appear, the invention consists 45 in the features of novelty in substantially the construction, combination and arrangement of the several parts hereinafter more fully described and claimed and shown in the accompanying drawing illustrating this 50 invention, and in which—

Figure 1 is a view partly in elevation, partly in section and with parts broken away 55 of a portion of a sheet metal drawing press having cushioning devices applied thereto and connected with the pin or pressure plate

by means of a connection constructed in accordance with the principles of this invention.

Figure 2 is an enlarged detail vertical section view of the connection. 60

Figure 3 is a top plan view of Figure 2 with parts broken away.

Referring more particularly to the drawing the numeral 10 designates generally the bed plate of a sheet metal drawing press 65 and 11 and 12 are the reciprocating members which are adapted to be reciprocated in any suitable manner well known in this art.

Supported beneath the bed plate 10 in any suitable manner are a plurality of cushioning devices each of which embodies a cylinder 13 to which fluid is supplied from any suitable source through piping 14. 70

Reciprocable in the cylinders are pistons (not shown) and connected with each of 75 the pistons is a piston rod 15, which projects beyond the end of the cylinder.

Disposed beneath the bed plate 10 is a pressure or pin plate 16 which is supported by means of the piston rods 15 and these 80 piston rods are connected with the pressure or pin plate 16. Formed on the end of each of the piston rods 15 is a ball shaped member of any desired and suitable configuration and this member may be formed integral with the end of the piston rod or may be formed separately therefrom as shown. When formed separately therefrom, the member 17 is connected with the extremity of the piston rod 15 in any suitable manner 90 preferably through the medium of a screw 18 which screws into each of the parts and when in position, the parts may be held against rotative displacement by means of a suitable locking screw 19. 95

The extremity 17 of the piston rod projects into a casing 20, which latter is secured in any desired or suitable manner to the lower face of the pressure or pin plate 16, preferably through the medium of fastening 100 bolts 21 which pass through suitable apertures 22 in a flange 23 on the casing 20.

A removable cover plate 24 is secured to the casing 20 in any suitable manner such as by means of fastening screws 25 and the bottom of the casing is provided with an opening 26 therethrough, which is of a diameter considerably greater than the external diameter of the piston rod 15 and the adjacent portion of the stem 27 on the ball 110

shaped member 17 so as to permit the piston rod 15 and the casing 20 to be rocked relatively one with respect to the other.

When the extremity 17 is disposed within 5 the casing 20 the upper spherical face 28 thereof has contact with the lower face of the plate 24 and an annular member 29 having a seat 30 contacts with the opposite face of the extremity 17. This member 29 is of 10 an external diameter somewhat less than the internal diameter of the casing 20 so as to permit the member 29 to be bodily moved when the casing 20 and piston rod 15 are rocked with respect to each other.

15 The member 29 is supported by means of an annular member 31 which is also provided with an opening 32 of a diameter considerably greater than the external diameter of the piston rod 15. The external 20 diameter of the member 31 is such that it will snugly fit within the casing 20 and will be held against bodily movement in a direction edgewise of the member.

25 The member 30 is supported by means of resilient elements 33 preferably in the form of coil springs, any number of which may be provided, four being here shown, and one extremity thereof engages and rests against the lower face of the member 31, while the 30 other extremities thereof rest upon the bottom of the casing 20. A pin or projection 34 may be provided which is secured to the bottom of the casing 10 and projects therewith into and within the resilient elements 33 so 35 as to hold the latter in position.

The stress of these resilient elements 33 is such that under normal conditions the member 31 will cause the bearing 30 in the member 29 to contact with the face of the 40 extremity 17 and this will hold the upper surface of the extremity 17 in contact with the lower face of the plate 24 and prevents the piston and piston rods from dropping with respect to the pin or pressure plate 16 45 when the weight of the piston and piston rod overcomes the pressure in the cylinders 13.

With this improved construction it will be manifest that the surface 28 of the extremities 17 of the piston rods 15 will be maintained in contact with the lower face of the respective plates 24 so that when pressure is exerted upon the die 35 which is supported by the pins 36, and which latter rest upon 55 the pin or pressure plate 16, the piston rods 15 will be lowered against the stress of the fluid pressure in the cylinders 13.

Should greater pressure be exerted upon the plate 16 at one point than at another point, the tendency would be to tilt the plate 16 or cause it to be moved out of a horizontal position and will tilt the same with respect to the piston rods 15. By reason of the flexible connection between the piston rod 60 15 and the plate 16 it will be manifest that

the plate 16 may be rocked or tilted with respect to the piston rods 15 without causing any injury to the parts and without causing the plate 16 to be relieved of the resistance of any of the fluid pressure in the cylinder 70 13. During this tilting movement the plate 16 will turn upon the bearings formed by the faces 28 of the piston rods and the lower faces of the respective plates 24.

When this connection is applied to the 75 plate 16 the plate 26 will rest flat against the lower face of the plate 16.

When the pin or pressure plate 16 is being elevated the piston rods 15 and piston connected thereto will be held against dropping away from the plate 16 upon the reduction of the pressure in the cylinder 13, through the medium of the resilient members or springs 33 which hold the bearing plate 29 against the extremity 17 of the piston rod and also holds the surface 28 of the extremity 17 against the plate 24.

It will be manifest that this improved construction may be applied to any machine now on the market which have similar cushions connected thereto, without altering the construction of the other machine and may as readily be detached therefrom.

While the preferred form of the invention has been herein shown and described it is 95 to be understood that various changes may be made in the details of construction and in the combination and arrangement of the several parts, within the scope of the claims, without departing from the spirit of this 100 invention.

What is claimed as new is:—

1. In a sheet metal drawing press a pressure member, a cushioning device therebelow, means connecting the cushioning device with the pressure member, said connecting means embodying a member having a curved extremity on one end thereof, and resiliently yielding means other than the cushioning device for maintaining the said curved extremity in abutment with the said pressure member, said connecting means permitting the pressure member to tilt with respect to the said cushioning means.

2. In a sheet metal drawing press a pressure plate, a fluid pressure cushioning device therebetween and embodying a cylinder and piston reciprocable therein, a piston rod, and means connecting the end of the piston rod directly with the said plate, the said connecting means including mechanism permitting a relative rocking movement between the plate and piston rod.

3. In a sheet metal drawing press a pressure plate, a fluid pressure cushioning device therebetween and embodying a cylinder and piston reciprocable therein, a piston rod, means connecting the end of the piston rod directly with the said plate, the said connecting means including mechanism permitting

- a relative rocking movement between the plate and piston rod, and means other than the fluid pressure for maintaining the end of the piston rod in abutment with the plate.
- 5 4. In combination a pressure cushion, including a rod like element, a pressure member separate therefrom, a coupling between said element and member, said coupling embodying a ball like device on the end of said rod, a casing connected with the said member and in which casing the ball is disposed, and a yielding seat having engagement with the said ball on the side thereof adjacent its point of connection with the said rod.
- 10 5. In a sheet metal drawing press a pressure plate, a cushioning device therebelow, means connecting the cushioning device with the plate, said means embodying a ball like device on one of said members, said plate and cushioning device having a ball like device connected with one and a casing connected with the other and in which casing the said ball like device is disposed, means other than the cushioning device for maintaining said ball like device against one wall of the casing, the said means embodying an annular seat contacting with the ball, an annular member contacting with the last recited member, and resilient means disposed between the second annular member and the bottom of the casing.
- 15 6. In a sheet metal drawing press a pressure plate, a cushioning device therebelow, means connecting the cushioning device with the plate, said means embodying a closed casing having an opening through the bottom thereof, a rod like device projecting into the casing through said opening, a knob like formation on the end of the rod and within the casing, the external diameter of the rod being considerably less than the diameter of said opening, a bearing within the casing and contacting with the lower face of said formation, and resilient means also within the casing disposed between said bearing and the bottom of the casing and operating independently of the cushioning device to hold the bearing against said formation and the latter against the opposite wall of the casing.
- 20 7. In a sheet metal drawing press a pressure plate, a cushioning device therebelow, means connecting the cushioning device with the plate, said means embodying a closed casing having an opening through one wall thereof, a rod like device projecting into the casing through said opening, the diameter of said rod being considerably less than the diameter of said opening, the extremity of the rod being convexed and abutting one of the walls of the casing, and means within the casing and operating independently of the cushioning device for holding said extremity of the rod against the casing wall, the said means permitting a rocking move-
- ment of the rod and casing, one with respect to the other.
- 25 8. In combination a closed casing having an opening through one wall thereof, a rod like device projecting into the casing through said opening and being of a diameter considerably less than the diameter of said opening, an enlarged formation on the end of the rod and having a convexed surface, an annular bearing member encompassing the rod and contacting with a portion of the face of said formation, a second annular member within the casing and contacting the first said member, and resilient elements also within the casing and disposed between the said second annular member and the base of the casing and operating to hold another portion of the face of the said enlarged formation in rocking engagement with the casing wall.
- 30 9. In combination a closed casing having an opening through one wall thereof, a rod like device projecting into the casing through said opening and being of a diameter considerably less than the diameter of said opening, an enlarged formation on the end of the rod and having a convexed surface, an annular bearing member encompassing the rod and contacting with a portion of the face of said formation, a second annular member within the casing and contacting the first said member, and resilient elements also within the casing and disposed between the said second annular member and the base of the casing and operating to hold another portion of the face of the said enlarged formation in rocking engagement with the casing wall.
- 35 10. In combination a closed casing having an opening through one wall thereof, a rod like device projecting into the casing through said opening and being of a diameter considerably less than the diameter of said opening, an enlarged formation on the end of the rod and having a convexed surface, an annular bearing member encompassing the rod and contacting with a portion of the face of said formation, a second annular member within the casing and contacting the first said member, and resilient elements also within the casing and disposed between the said second annular member and the base of the casing and operating to hold another portion of the face of the said enlarged formation in rocking engagement with the casing wall, the first recited annular member being of a diameter somewhat less than the internal diameter of the casing and the second recited annular member being maintained against bodily edgewise movement in the casing.
- 40 11. In combination a closed casing having an opening through one wall thereof, a rod like device projecting into the casing through said opening and being of a diameter considerably less than the diameter of said opening, an enlarged formation on the end of the rod and having a convexed surface, an annular bearing member encompassing the rod and contacting with a portion of the face of said formation, a second annular member within the casing and contacting the first said member, resilient elements also within the casing and disposed between the said second annular member and the base of the casing and operating to hold another portion of the face of the said enlarged formation in rocking engagement with the casing wall, the said formation being separate from said rod, and means detachably securing the said formation to the rod.
- 45 12. In combination a closed casing having

an opening through one wall thereof, a rod like device projecting into the casing through said opening and being of a diameter considerably less than the diameter of 5 said opening, an enlarged formation on the end of the rod and having a convexed surface, an annular bearing member encompassing the rod and contacting with a portion of the face of said formation, a second 10 annular member within the casing and contacting the first said member, resilient elements also within the casing and disposed between the said second annular member and the base of the casing and operating to 15 hold another portion of the face of the said enlarged formation in rocking engagement with the casing wall, the said formation being separate from said rod, and a screw device housed within the rod and said formation 20 for securing them together.

12. In combination a closed casing having an opening through one wall thereof, a rod like device projecting into the casing through said opening and being of a diam-

eter considerably less than the diameter of 25 said opening, an enlarged formation on the end of the rod and having a convexed surface, an annular bearing member encompassing the rod and contacting with a portion of the face of said formation, a second 30 annular member within the casing and contacting the first said member, resilient elements also within the casing and disposed between the said second annular member and the base of the casing and operating to 35 hold another portion of the face of the said enlarged formation in rocking engagement with the casing wall, the said formation being separate from the said rod, a screw device housed within the rod and 40 said formation for securing them together, and a fastening device for maintaining the rod and said formation against relative movement.

In testimony whereof I have signed my 45 name to this specification, on this 26th day of May, A. D. 1925.

FREDRICH J. RODE.
